UNITED STATES PATENT OFFICE.

ERIK ANDREW WACKT, OF SYCAMORE, ILLINOIS.

DESIGN FOR TAILOR'S SHEARS.

57,749.

Specification for Design.

Patented Apr. 26, 1921.

Application filed October 9, 1919. Serial No. 329,618. Term of patent 7 years.

To all whom it may concern:

Be it known that I, ERIK A. WACKT, a citizen of the United States, residing at Sycamore, in the county of De Kalb and State of Illinois, have invented a new, original, and ornamental Design for Tailors' Shears, of which the following is a specification, reference being had to the accompanying drawing, forming part thereof.

The figure is a plan view of a pair of tailors' shears, showing my new design.

I claim:

The ornamental design for tailors' shears, as shown.

ERIK ANDREW WACKT.
